UNITED STATES PATENT OFFICE.

WILLIAM F. HERDRICH, OF CHICAGO, ILLINOIS, ASSIGNOR OF TWO-THIRDS
TO SIMON LICHTENSTEIN AND ADOLPH REINACH, OF SAME PLACE.

COMPOUND LOCK.

SPECIFICATION forming part of Letters Patent No. 613,629, dated November 1, 1898.

Application filed May 11, 1898. Serial No. 680,338. (No model.)

To all whom it may concern:

Be it known that I, WILLIAM FREDERICK HERDRICH, a citizen of the United States, residing at Chicago, in the county of Cook and State of Illinois, have invented certain new and useful Improvements in Compound Locks, of which the following is a specification.

The object of my invention is to provide a simple, economical, and efficient compound lock; and the invention consists in the features, combinations, and details of construction hereinafter described and claimed.

In the accompanying drawings, Figure 1 is a side elevation of a lock and case constructed in accordance with my improvements, having one of the side plates of the case removed, so as to show the interior operative mechanism; Fig. 2, a similar view of the lock with the tumblers removed; Fig. 3, an enlarged cross-sectional elevation taken on line 3 of Fig. 1. Figs. 4, 5, 6, 7, and 8 are elevations of the compound tumblers; Fig. 9, a side elevation of the socket and operating-lever, and Fig. 10 a side elevation of the key.

In the art to which this invention relates it is well known that the opening of an ordinary lock by means of a single key, piece of wire, or case-knife is not very difficult. My invention is intended to overcome this objection by providing a compound lock in which there are two bolts operated by one key which are locked in their "in" and "out" positions.

In constructing a lock in accordance with my improvements I provide a case or frame A, of the desired size, shape, and strength, adapted to contain and hold the different parts in their operative positions. This case may be made in any of the usual manners—that is, provided with a face-plate a and cap a', which cap is secured to the main portion of the case by means of screws which enter the openings a², as shown particularly in Fig. 1.

For the purpose of locking a door or other movable structure in connection with an immovable portion I provide a slide-bar B, which has two "dead" or locking bolts b and b' integrally secured to it, so as to be moved through the face-plate and lock the desired article. In order to operate this locking-bolt, I provide a key-socket C, which has an oper-

ating lever or arm D integrally secured to it and which is pivotally mounted in the case of the lock, so that as it moves it operates to push the dead-bolt out on the upper side, as shown in Fig. 2, and to strike it on the opposite part when it is moving it in.

In order to lock the dead-bolts in their out and in positions, a set of compound tumblers E', E², E³, E⁴, and E⁵ is provided, arranged alternately, so that one set of three tumblers is pivoted to the case by means of the stud e and the other set of two tumblers pivoted to the case diametrically opposite on the stud e'. These tumblers are so arranged in connection with the key-socket that they span or encompass the same and are cut in such a manner that they can be acted on by the projections g and g' on the key G. Each end of the tumblers diametrically opposed is provided with recesses or slots E and E⁶, so arranged that when the key turns with the socket in one direction it contacts the tumblers, so as to swing them on one pivot and bring the openings E in alinement and allow the pin b² of the slide-bar to pass into the enlarged recess of the opening to lock such bolt in that (the outer) position. When the dead-bolts are in their outer or locked position, the turning of the key in the opposite direction will swing the tumblers on the pivot e, bringing the openings E⁶ into parallelism or alinement, so that the pin b³ may pass in through the same and into the enlarged recess and hold the dead-bolt at its inner or unlocked position.

From the foregoing description of construction and operation it will be seen that the dead-bolt is a compound dead-bolt and locked in its inner and outer positions, thus preventing either the locking or unlocking of the bolt without the assistance of a key constructed for that purpose. Further, it will be seen that both sides of the key—that is, the part that enters the key-socket—are provided with projections g and g' of a different combination, thus rendering the key in its nature compound and therefore more difficult to counterfeit or take an impression from.

When the dead-bolts have been thrown in or out by the action of the key in the socket, it is highly desirable to vibrate the tumblers on their pivots, so as to bring them down into

the position shown in Fig. 1, and thereby securely lock the sliding bar, with its dead-bolts, from further reciprocations or movements until the tumblers have been vibrated. In order 5 to accomplish this result, the key-socket is constructed so that the portion C' to one side of the longitudinal center extends out farther than the opposite side and acts as a cam. This cam portion of the key-socket strikes 10 the edge e^2 of the central perforation in the tumblers, vibrating the same on their pivots, so as to bring the narrow apertures E and E^6 of the locking-slots out of alinement with the studs b^2 and b^8 , and thus hold the parts against 15 further movement.

I claim—

1. In a compound lock the combination of a sliding bar provided with two dead-bolts, a set of tumblers oppositely pivoted and provided with a substantially central perforation and two locking slots or perforations in the outer edge, a pin or pins on the sliding bar adapted to enter the locking slots or perforations and lock the dead-bolts in their outer and inner positions, and key mechanism adapted to pass through the central apertures in the tumblers and operate the same to lock or unlock the dead-bolts, substantially as described.
2. In a compound lock, the combination of a case portion, a sliding bar movably mounted therein and provided with two dead-bolts secured integrally therewith and with a substantially central irregular opening, a key-

socket rotatably mounted in the case and 35 provided with an arm adapted to contact the sliding bar at each side thereof and move it in or out, a set of tumblers oppositely pivoted provided with a substantially central opening and locking slots, perforations or 40 openings in the outer edge thereof, pins on the sliding bar adapted to enter each of such openings and hold the dead-bolts in their locked and unlocked positions, and key mechanism adapted to enter the key-socket and 45 operate the tumblers so as to permit the locking or unlocking of the dead-bolt, substantially as described.

3. In a compound lock, the combination of a sliding bar provided with two dead-bolts, a 50 set of tumblers oppositely pivoted and provided with a substantially central perforation and two elongated perforations in the outer edge thereof, a pin or pins on the sliding bar adapted to enter the locking slots or 55 perforations to lock the dead-bolts in their outer and inner positions, and a key-socket rotatably mounted in the case portion to receive a key and provided with a cam portion adapted to strike the tumblers and vibrate 60 them after the pin or pins have entered the locking perforations so as to lock such pins in the slot or slots, substantially as described.

WILLIAM F. HERDRICH.
